THIS ATTORNEY.

UNITED STATES PATENT OFFICE.

HERMAN COHN, OF NEW YORK, N. Y.

DESIGN FOR A VENDING CARD FOR BEAD STRINGS.

Application filed June 7, 1929. Serial No. 31,580. Term of patent 14 years.

To all whom it may concern:

Be it known that I, HERMAN COHN, a citizen of the United States, residing at New York, in the county of New York and State of New York, have invented a new, original, and ornamental Design for Vending Card for Bead Strings, of which the following is a specification, reference being had to the accompanying drawing, forming part thereof.

I claim:

The ornamental design for a vending card for bead strings as shown.

HERMAN COHN.
